INSTRUMENT PANEL WITH SPACED CUSHIONING DEVICES

Filed Jan. 16, 1930

UNITED STATES PATENT OFFICE

MICHAEL V. TERRY, OF FLINT, MICHIGAN, ASSIGNOR TO A C SPARK PLUG COMPANY, OF FLINT, MICHIGAN, A COMPANY OF MICHIGAN

INSTRUMENT PANEL WITH SPACED CUSHIONING DEVICES

Application filed January 16, 1930. Serial No. 421,142.

The present invention relates to novel types and arrangements of resilient spacers for use in the yieldable support of glass plates; and, as implied by the above title, said invention has been developed with particular reference to the application of a gentle but adequate supporting pressure to the inner or concealed sides of such glass plates as are now commonly embodied in instrument panel organizations.

The novel devices referred to may be of very simple construction, and spaced apart at any desired intervals; and, in preferred embodiments, cushioning elements thereof are supported or guided by parts formed or carried by one or more inner metallic plates, such as have heretofore been employed at the inner side of a glass closure plate of the type referred to.

In instrument panels of the mentioned type, it has been common to provide, on the "forward" or concealed side of a glass plate, usually common to several instruments, one or more inner metallic plates,—a so-called "face plate" being often interposed between said glass plate and a comparatively heavy "backing" plate, suitable for the support of instruments; and flanges provided upon one or both of these inner metallic plates have often been brought into juxtaposition to a flange provided upon a bezel-carrying finishing or cover plate upon the exposed "rearward" or "outer" side of said glass plate. In these known constructions, more or less continuous strips of cushioning material have commonly been employed near the edges of said plate and upon both sides thereof; but the known constructions referred to have provided space for only practically continuous and usually comparatively thin cushioning strips in contact with the concealed or "forward" side of the glass; and irregularities in the opposed surfaces, and/or inequalities in the elasticity of the stocks in the pressures applied therethrough have been found to result in undue loss by breakage. It is accordingly an object of the present invention, whether employing one or more metallic plates upon the inner side of the glass, to provide panel organizations which include separately formed

and suitably spaced cushioning elements,—which are disposed with their axes at right angles to the planes of said plates and which exceed in length the distance between the mentioned glass plate and the adjacent metallic plate.

Other objects of this invention, including the optional use of upwardly projecting points and/or thimbles, carried by one or both of the mentioned inner metallic plates, and optionally involving the use of compression springs in some or all of said cushioning devices, may be best appreciated from the following description of alternative embodiments of said invention, taken in connection with the appended claims and accompanying drawings.

Fig. 1 is a forward-looking elevational view showing part of a dash and one type of instrument panel organization in which the present invention may be utilized in holding a glass closure plate, common to several instruments, in position,—a part being broken away.

Fig. 2 is a sectional view, which may be regarded as taken in the general manner suggested by the broken line 2—2 of Fig. 1,—various types of cushioning devices, all within the scope of the present invention, being shown as incorporated therein.

Fig. 3 is a larger scale sectional view, corresponding to the left hand portion of Fig. 1 but with parts cut or broken away to various levels.

Fig. 4 is a detailed perspective view, taken from the general direction suggested by the arrows 4 of Figs. 1 and 2 and illustrating the use of a rectangular type of cushioning element slidably held by guides cut from an intermediate metallic plate.

Fig. 5 is a detailed perspective view comparable with Fig. 4, but showing only a cylindrical cushioning element,—this being suggested for alternative use within rectangular or other guiding means of the general character shown in Fig. 4.

Figs. 6-10, inclusive, are detailed views suggesting various alternative forms and modes of embodiment of cushioning devices, these being suitable for either conjoint

or exclusive use, and all of these views being taken substantially as implied by the line 6—10 of Fig. 1.

Referring first to conventional features shown in Figs. 1, 2 and 3, a dash or instrument board 11 is shown as apertured suitably to the reception of an instrument panel organization comprising a main metallic "backing" plate 12 (carrying any desired instruments 13), an apertured intermediate "face" plate 14, a glass closure plate 15, and a bezel-providing finishing plate or cover plate 16,—the bezel 17 thereof being adapted to interfit within the mentioned opening in the dash or instrument board 11. The bezel is shown as comprising a longitudinal depressed portion 18, centrally engaging a cushioning strip 19, which may extend entirely around the glass plate 15 near the edge thereof; the mentioned metallic plates may be rigidly held in their assembled relationship by any suitable means,—such as an inward rebending of a flange 20, provided at the periphery of one of said plates and adapted to enclose substantially parallel flanges 12' and 14', shown as provided upon the respective plates 12 and 14; and, assuming that both of the mentioned inner plates are employed, the plate 12 may be formed of a material sufficiently heavy to permit the use of means such as screws 21, entering threaded bosses 22, shown as inwardly projecting therefrom, in the support of the mentioned instruments 13.

Coming now to more novel features, the plate 14 is shown as provided with a plurality of spaced openings 23, adapted respectively to receive separate spacing and cushioning devices,—including cylindrical, prismatic or other cushioning elements disposed with their axes at right angle to the planes of the mentioned plates and exceeding in length the distance between the apertured metallic plate and the glass plate to be cushioned. Incidentally to the piercing of the plate 14, to provide the mentioned apertures 23, inwardly extending angular or other guide elements 24 may be so shaped and disposed as slidably to receive cylindrical or other prismatic cushioning elements,—such for example, as are shown at 25, in Fig. 4, and at 25a, in Fig. 5. One end of each of these cushioning elements is shown as extending into engagement with the glass plate 15, a suitable pressure being applied to the other end thereof by one of the plates 12 or 14, whether directly or indirectly.

The cross-sectional outline of the cushioning elements may naturally depend somewhat upon the selection made among alternative materials available therefor; but it will be obvious that they may be formed from materials such as cork or rubber or felt or compositions thereof, cut to size and inserted in the openings 23, but not necessarily cor-

responding in outline with the cross-sectional configuration thereof. Cork has an advantageous non-slipping quality; and various units may be inserted in advance in one or the other of the inner plates, or added during or after the assembly of the described organization.

It is suggested in Fig. 6 that, instead of being engaged by the plate 12b, cushioning elements 25b may be loosely fitted within thimbles 26b, the latter being inserted in circular or other openings 23b in an intermediate plate 14b; and in Fig. 7 an open-ended thimble 26c is shown as receiving not only a cushioning element in the form of a flanged stud or button 25c but also a compression spring 25c',—to which compression may be applied by a main backing plate 12c.

In the construction shown in Fig. 8, an inner metallic plate 14d is shown as apertured to receive comparatively rugged thimbles 26d, each of which may receive not only a cushion button 25d but a compression spring 25d'; and Fig. 9 illustrates another simple embodiment of the invention,—in which a plate 12e may be provided with bosses 26e, adapted to receive cushioning elements 25e. For a dust-excluding or other effect, a thimble or disc 26e' may be inserted, and/or the boss 26e may be provided with integral prongs 24e, inwardly bent from such positions as are indicated in dotted lines and adapted then to engage and retain the cushioning elements 25e or interposed discs 26e',—interposed plates 14e, if provided, being suitably apertured, as at 23e.

Fig. 10 illustrates an optional embodiment which is shown as including substantially all of the mentioned features and additional features. An open-ended thimble 26f slidably receives a cushioning element 25f; and the main plate 12f is shown as providing an integral thimble or boss 26f'. The latter may include prongs 24f', inwardly bent to retain a disc 28f'; and a compression spring 25f' is shown as retained between the disc 28f' and a companion disc 28f, integral with thimble 26f or otherwise movable relatively to boss 26f'. If desired, this boss may be externally threaded, as at 29f, for the reception of a threaded cap 26f'', or like means for applying axial pressure to the cushioning element 25f and/or the spring 25f'; and, in order to permit the use of this embodiment of the invention in the incidental retention of an instrument 13f, a central boss 30f, shown as directly engaging the plate 28f', may, if desired, be internally threaded in readiness for the optional employment of a screw 21f, shown as directly engaging an instrument flange 13d. This figure incidentally suggests a one-instrument construction in which the use of any intermediate metallic plate is unnecessary.

The general mode of construction and use

of all embodiments of the present invention being clearly indicated above, it may be again emphasized, in conclusion, that the described devices obviate the necessity for providing means to retain substantially continuous gaskets between the inner metallic plates and the transparent closure plates of instrument board organizations and thereby reduce expense and largely obviate breakage of glass in production, handling, assembling and/or actual use of such organizations upon motor vehicles,—the mentioned breakage having been found to result largely from uneven pressures applied through long and often relatively thin inner gaskets, as heretofore used with their longitudinal axes parallel with the mentioned plates; and it will be seen that this invention may provide for a separate adjustment of a pressure applied through each cushion, if and where desired. It also provides, in various embodiments of the invention, for an application of pressure to the cushioning elements directly or indirectly by the main backing plate of a panel organization and/or by an intermediate plate, as desired,—reliance upon the former being found advantageous by reason of the comparative uniformity and flatness of the more rugged backing plates.

The use of a lock nut is suggested at 31/ in that unnecessarily complicated form shown in Fig. 10; and it will be noted that the prongs 24/ and other features of this form are not requisite to the operativeness thereof. This embodiment, however, like the very simple embodiment shown in Fig. 9, is one that admits of the insertions of the cushioning elements from either direction, even after a main backing plate is in place. On the other hand, angular or other projections such as are shown at 24, and also the thimbles 26b, 26f, 26f', 26f'', as one or more may be employed, need not positively grip the cushioning element therein,—being intended rather as guides and/or stops to hold the axes of the same substantially at right angles to the glass or other element to be cushioned; and the provision of flanges 32b, etc. (various characters not specifically mentioned herein being applied to the drawings in a manner consistent with the indicated usage) predetermines a direction of insertion. It also renders the mentioned thimbles (and thereby the devices comprising the same) self-retaining, in use, regardless a degree of imperfection of fit,—some of these devices being entirely suitable for separate manufacture and sale, to be used in any suitable openings.

Although the foregoing description has included reference to but a limited number of alternative embodiments, it will be understood not only that various features of the present invention are capable of independent use, but also that numerous modifications, additional to those mentioned, can easily be de-

vised by skilled workers who may become acquainted with the foregoing,—all within the scope of the present invention.

I claim:

1. An instrument panel comprising: a 70 glass closure plate; a plurality of metallic plates disposed on the inner side thereof, one of said plates being provided with spaced apertures; and separate cushioning elements extending through said apertures into contact with said glass plate,—said cushioning elements being pressed thereto by one of said metallic plates. 75

2. An instrument panel comprising: a 80 glass closure plate; a plurality of metallic plates disposed on the inner side thereof, one of said plates being provided with spaced apertures; and separate cushioning elements extending through said apertures into contact with said glass plate,—said cushioning 85 elements being pressed thereto by one of said metallic plates and one of said metallic plates being provided with guide means for said cushioning elements.

3. An instrument panel comprising: a 90 glass closure plate; a plurality of metallic plates disposed on the inner side thereof, one of said plates being provided with spaced apertures; and separate cushioning elements extending through said apertures into contact with said glass plate,—said cushioning elements being pressed thereto by one of said metallic plates, and a cushion-carrying metallic plate being disposed in front of said glass plate and retained by means comprising 95 a flange on one of said plates. 100

4. In means for applying yielding pressure to the inner side of a glass plate comprised in instrument panel which includes also an inner metallic plate: cushioning elements 105 whose longitudinal axes extend substantially at right angles to the planes of said plates and exceed, in length, the distance between said plates, said elements engaging said glass plate, means for applying pressure to said 110 elements so that they serve to hold the glass plate in position,—said metallic plate being provided with separate apertures through which separate cushioning elements extend and means for securing said metal plate in 115 fixed relation to said glass plate.

5. In an instrument panel the combination of an apertured metallic plate, a glass plate extending parallel with the metallic plate, a cushioning element which extends at right angles to said plates and through an aperture in said metallic plate; guide means for said element; and means for applying to said element substantially axial pressure in the direction of said glass plate. 120 125

6. In an instrument panel the combination of an apertured metallic plate, a glass plate extending parallel with the metallic plate, a cushioning element which extends at right angles to said plates and through an aperture 130

in said metallic plate; a guide means for said element; and means for applying to said element substantially axial pressure in the direction of said glass plate,—said guide means being carried by said metallic plate.

7. In an instrument panel the combination of an apertured metallic plate, a glass plate extending parallel with the metallic plate, a cushioning element which extends at right angles to said plates and through an aperture in said metallic plate; guide means for said element; and means for applying to said element substantially axial pressure in the direction of said glass plate,—said guide means including projections from said metallic plate.

8. In an instrument panel the combination of an apertured metallic plate, a glass plate extending parallel with the metallic plate, a cushioning element whose axis extends at right angles to said plates; guide means therefor; and means for applying to said element substantially axial pressure in the direction of said glass plate,—said guide means including a thimble which slidably receives said cushioning element.

9. In an instrument panel the combination of an apertured metallic plate, a glass plate extending parallel with the metallic plate, a cushioning element engaging said glass plate; guide means therefor; and means for applying to said element substantially axial pressure in the direction of said glass plate,—said guide means including a thimble which is open at both ends, slidably to receive said cushioning element.

10. In an instrument panel the combination of an apertured metallic plate, a glass plate extending parallel with the metallic plate, a cushioning element contacting said glass plate and extending substantially at right angles thereto; guide means for said element; and means for applying to said element substantially axial pressure in the direction of said glass plate,—said last-mentioned means including a compression spring.

11. In an instrument panel the combination of an apertured metallic plate, a glass plate extending parallel with the metallic plate, a cushioning element contacting said glass plate and extending substantially at right angles thereto; guide means for said element; and means for applying to said element substantially axial pressure in the direction of said glass plate,—said last-mentioned means acting through a compression spring, and said guide means including a thimble which receives said spring.

60. In testimony whereof I affix my signature.
MICHAEL V. TERRY.
